UNITED STATES PATENT OFFICE.

JOHN B. BAXTER, OF WATERVLIET, NEW YORK, ASSIGNOR TO COVERT MANUFACTURING COMPANY, OF WATERVLIET, NEW YORK, A CORPORATION OF NEW YORK.

HOOK.

1,240,810.

Specification of Letters Patent. Patented Sept. 25, 1917.

Application filed October 29, 1915. Serial No. 58,672.

To all whom it may concern:

Be it known that I, JOHN B. BAXTER, a citizen of the United States, residing at Watervliet, in the county of Albany and State of New York, have invented certain new and useful Improvements in Hooks, of which the following is a specification, reference being had therein to the accompanying drawing.

10 This invention relates to improvements in hooks, more particularly snap hooks and has for its primary object the provision of an improved mounting for the spring customarily employed for automatically closing and normally retaining in closed position the tongue of the hook.

In the art of snap hooks wherein, commercially, devices must be provided for sale at slight cost, and necessarily manufactured 20 at minimum expense, much work has been done in simplifying the number and formation of the parts while retaining adequate strength and rigidity of the ultimate article, primarily among which parts is of course the casting for the body of the hook, constituting the shank and bill portions thereof. The special snap hook to which the present improvements appertain is that general style embracing a casting having 30 a shank and bill, a pivoted tongue in the nature of a sheathing adapted to underlie the end of the bill and embrace the sides of the shank, and a spring within the sheathing and between the tongue and the shank 35 constantly exerting a pressure to throw the tongue into closed relation with the bill.

Turned over lugs, upwardly projecting flanges and lugs, locking pins and other means have been utilized to retain such 40 springs, to which I have just alluded, in operative association with the other parts of the snap hook, but these structures have called for extra parts, relatively expensive castings both in the use of unnecessary metal 45 and extra skill and means in the casting operation, and in instances, the spring retaining means are comparatively weak, while in other instances the parts are loosely assembled with the attending disadvantages 50 contrary to the much desired elimination of unnecessary rattling or noise, especially in harness use.

With the foregoing in mind, my improvements have been inspired by an effort to 55 produce a snap hook of a compact firmly

held association of the fewest possible parts so related as to produce all necessary strength, expeditious and inexpensive casting and assembling, and devoid of undue looseness or play of the parts in the assembled product, all tending toward permanency, in preventing disarrangement of the coöperating elements, silent operation and general efficiency.

The preferred embodiment of the invention includes the provision of a hook, the shank of which along one edge, is provided with a receiving groove for the end of a wire spring, said groove being of relative size to closely confine the spring permanently in place to prevent lateral play thereof, and preferably one wall of the groove being shaped to exert a constant action in seating and retaining the spring permanently in its seat,—the foregoing, as distinguished from the provision of lugs or the like which require special casting, are capable of easy breakage, and are so associated as to permit a play of the spring therebetween, or the escape of the spring by a slight movement to ride laterally thereover. In the lug construction also the end of the spring is exposed, and unless covered by some additional means as by a forwardly extending part of the sheathing, the ring or other engaged device may operate to dislodge the spring, whereas in my present improvements the spring is below the normal plane of the edge of the shank in which the groove is formed, and the ring cannot engage the end of the spring but simply rides over the edge of the shank below which the spring is confined as will more fully hereinafter appear from the specific description to be now given, in connection with the accompanying drawings forming part hereof, and wherein the above mentioned preferred embodiment of the invention is illustrated.

In the drawings: 100

Figure 1 is a side elevation of a complete snap;

Fig. 2 is a longitudinal sectional view;

Fig. 3 is a transverse sectional view, looking toward the pivot end of the device, and 105

Fig. 4 is a similar view, looking toward the bill.

Referring more specifically to the drawing, wherein like reference letters refer to 110

corresponding parts throughout the several views, A represents the shank, B the bill, and C the ordinary attaching loop at the end of the shank. Above the shank constituting an integral part thereof, I form a 5 spring seat D having a curved rear wall E and a side wall or base F, the latter being in the plane of the adjacent side of the shank. This side wall is perforated as at G 10 for a purpose as will presently appear.

Formed in the upper edge of the shank and merging into the curved rear wall of the spring seat is a groove H for the reception of the end portion i of a coiled wire spring 15 I, sleeved upon a rivet J passing through the side wall of the spring seat, and having an upper end portion or extension i' engaging the undersurface of a tongue K arranged to engage the bill of the hook at its free 20 end, and pivoted at its opposite end upon said rivet, said tongue being of U-shaped cross section, tapering rearwardly for obvious purposes, and constituting a sheathing for inclosing the spring and for overlapping the 25 sides of the shank to guide the tongue at all times in its movement and prevent lateral play or strain thereof on the rivet to which the tongue is pivoted.

The groove H in the upper edge of the 30 shank has a vertical wall h in the plane of the inner surface of the side wall of the spring seat, the groove being deepest immediately adjoining the wall just referred to, and the other combined base and side wall 35 of the groove h' inclines upwardly and outwardly from the bottom of said vertical wall to the upper edge of the shank. This formation tends to cause the end i of the spring, under its constant downwardly exerting pressure to ride into and be maintained in the deepest portion of the groove adjacent to the vertical wall thereof, and the same also tends to prevent any lateral or canting movement of the spring, because as 40 will be appreciated from the drawings, the end of the spring which is confined in this groove runs into the convolution of the coiled portion of the spring immediately adjacent to the side wall of the groove C, so that the 45 pressure of the end of the spring in the 50

groove is always in a straight line parallel to the groove.

It is of course understood that the upper end of the spring exerts a constant yielding pressure to maintain the tongue in engagement with the bill. 55

By having the entire lower end of the spring fitted in the groove below the upper edge of the shank, maximum space may be afforded within the bill between the same 60 and the tongue, the undercutting of the tongue being extended if desired backwardly beyond the forward end of the groove, if desired, without exposing the end of the spring to engagement by the ring or other 65 device engaged by the hook. Otherwise, as in the employment of confining lugs with the incidental exposure of the end of the spring, said end must be housed by the hollow tongue to prevent the ring or other device 70 overlapping the spring.

While I have herein disclosed one special embodiment of the invention, it will be apparent to persons skilled in the art that the invention is capable of embodiment in other 75 forms and devices as may be within the scope of the hereto appended claim.

I claim:

A snap hook of the character described comprising a shank having an upwardly extending wall at one side, and also provided with a bill and spring actuated tongue, the spring having a terminal adapted to engage the shank and the upper surface of the shank being inclined from the normal plane of said surface inwardly from the outer side edge of the shank to near the opposite side edge thereof to constitute a broad guiding face and seat, the deepest portion of the seat being located immediately adjoining the 80 said side wall of the shank so that the latter serves as an abrupt stop for the spring terminal in its travel down the inclined surface. 85

In testimony whereof I hereunto affix my signature in the presence of two witnesses. 90

JOHN B. BAXTER.
